UNITED STATES PATENT OFFICE.

LAWRENCE Y. SPEAR, OF GREENPORT, NEW YORK, ASSIGNOR TO ELECTRIC BOAT COMPANY, OF NEW YORK, N. Y., A CORPORATION OF NEW JERSEY.

COMPENSATING DEVICE FOR SUBMARINE BOATS.

SPECIFICATION forming part of Letters Patent No. 778,339, dated December 27, 1904.

Application filed August 1, 1903. Renewed May 24, 1904. Serial No. 209,594.

To all whom it may concern:

Be it known that I, LAWRENCE Y. SPEAR, of Greenport, in the county of Suffolk and State of New York, have invented certain new and 5 useful Improvements in Compensating Devices for Submersible and Submarine Boats, of which the following is a specification.

This invention relates to the class of submersible and submarine boats which carry 10 torpedoes and have means for expelling them; and it has for its object improved means for compensating the weight of torpedoes moved in a fore-and-aft direction within the boat with the purpose in view of maintaining 15 constant or very nearly constant the fore-and-aft center of gravity of the system at all times during the shifting and after the shifting of the torpedo.

In the accompanying drawing the figure is 20 a horizontal section of a submarine boat provided with the invention, the plane of the section being substantially in the axis of the hull of the boat. Only the forward part of the boat is shown and only such features of the 25 mechanism as are necessary to illustrate the present invention.

1 is the hull of the boat. 2 designates an 30 expulsion-tube therein, closed at its outboard end by a hinged cap 3 and at its inboard end by a door 4, both adapted to close water-tight. This door 4 is shown in the drawing as mounted on hinges and as thrown open. 5 and 5^a 35 designate torpedoes, the former being shown in position alined with the expulsion-tube and ready for entering the latter. 6 and 6^a are compensating water-tanks for the respective torpedoes.

The above features are known and need not be more particularly described.

40 7 and 8 are water-receptacles connected, respectively, with the expulsion-tube by pipes 9 and 10, controlled by stop-cocks or valves b' and b². The combined capacities of the two receptacles 7 and 8 equal substantially 45 that of the expulsion-tube, and the capacity of the receptacle 8 is equal to that of the expulsion-tube less the volume of water displaced by the torpedo when submerged, and

the capacity of the receptacle 7 is of course equal to the volume of water displaced by the 50 torpedo. The center of gravity of the tank 7 is substantially coincident with the fore-and-aft center of gravity of the expulsion-tube.

The receptacle 7 is coupled by a pipe 11 with the induction side of a rotary pump 12, 55 said pipe being controlled by a stop-cock b³, and the induction side of this pump is connected with the compensating tanks 6 and 6^a through a pipe 3, controlled by cocks b⁴ and b⁵. This pump 12 may be driven from any suitable 60 motor 14, but preferably an electric motor. The motor drives a windlass 15 through suitable gearing 16 and on this windlass winds a rope or other flexible connector 17, which carries at its end a bracket 18, 65 adapted to be secured to the stem or inboard end of the torpedo to be driven forward into the expulsion-tube.

19 is a compressed-air tank connected by a pipe 20 with the expulsion-tube, the flow being 70 controlled by a stop-cock a.

The operation is as follows: Suppose that at starting the cap 3 and door 4 are closed and the expulsion-tube is full of water, the tanks 6 6^a and receptacles 7 and 8 are empty and 75 the cocks all closed. The torpedo 5 is shifted into alinement with the expulsion-tube, as seen in the drawing, and the cocks b' and b² opened. The air-cock a is now opened and the water blown from the expulsion-tube into 80 the receptacles 7 and 8. The cocks a, b', and b² are now closed, the door 4 opened, and the bracket 18 secured to the torpedo. The parts are now in the position seen in the drawing, and the next step is to move the torpedo 5 85 forward into the expulsion-tube and to simultaneously transfer the water from the receptacle 7 to the compensating tank 6 gradually as the torpedo is moved forward, so as to avoid disturbing the fore-and-aft center of 90 gravity of the system. To effect this, the cocks b³ and b⁴ are opened and the pump 12 set in motion to transfer the water from the receptacle 7 to the compensating tank 6. Simultaneously the windlass 15 is rotated and 95 the rope 17 wound thereon, thus drawing the

torpedo into the tube, and by means of the cock b^3 the flow of the water back to the tank c may be regulated, so as to effect very accurate compensation.

5 Having thus described my invention, I claim—

1. A submarine or submergible boat having an expulsion-tube, a water-receptacle adjacent to said tube and having a capacity substantially equal to the displacement of the torpedo in the tube, a compensation-tank for the torpedo, a pump which transfers the water from the said receptacle to the said compensation-tank, a motor operating said pump, and 15 means for moving the torpedo into the tube simultaneously with the shifting of the compensating water.

2. A submarine or submergible boat having an expulsion-tube, a water-receptacle connected with said tube and having a capacity equal to the displacement of the torpedo sub-

merged in the tube and having its center of gravity substantially coincident with the fore-and-aft center of gravity of the expulsion-tube, a compensation-tank for the torpedo, a 25 pump which transfers the water from the said water-receptacle to said compensation-tank, a motor operating said pump, a windlass operated by said motor simultaneously with the pump, the rope wound upon said windlass 30 and provided with means for coupling it to the torpedo, and a controlling-cock in the pipe between the water-receptacle and the pump for regulating the flow.

In witness whereof I have hereunto signed 35 my name, this 27th day of July, 1903, in the presence of two subscribing witnesses.

LAWRENCE Y. SPEAR.
